UNITED STATES PATENT OFFICE.

GEORGE W. VEALE, OF CLEVELAND HEIGHTS, OHIO, ASSIGNOR TO THE EATON AXLE & SPRING COMPANY, OF CLEVELAND, OHIO, A CORPORATION OF OHIO.

BUMPER.

Application filed August 22, 1927. Serial No. 214,534.

This invention relates to bumpers for automobiles, having reference particularly to clamps for bumpers of the type in which a plurality of impact bars are spaced apart, one above the other.

The common practice heretofore has been to carry one plate of the clamp across the entire face of the bumper and to bend its ends so as to extend over the upper edge of the upper bar and the lower edge of the lower bar in order to prevent the bars from spreading, while the bars were definitely spaced apart by a spacing block integral with one of the clamp plates.

One of the objects of the invention, therefore, is the provision of a simple clamp of small size and light weight, which shall nevertheless effectively prevent the movement of the bars toward or away from each other, and without the use of a spacer block between the bars.

Another object is the provision of a clamp of this character which is especially adapted for use on bumpers having grooved impact bars.

Other objects and features of novelty will appear as I proceed with the description of that embodiment of the invention which, for the purposes of the present application, I have illustrated in the accompanying drawing, in which

Figures 1 and 2 are plan and elevational views, respectively, of a bumper embodying my invention.

Figure 3 is a transverse vertical section taken substantially on the line 3—3 of Figure 2, but on a larger scale.

Figure 4 is a front view of the outer plate of the clamp employed in the construction of Fig. 3.

Figure 5 is a sectional view corresponding to Fig. 3, but showing a modification, and

Figure 6 is a front view of the outer plate of the clamp shown in Figure 5.

In Figures 1, 2 and 3 I have illustrated a bumper comprising a pair of vertically spaced impact bars 10 and 11. These bars are evenly spaced for a distance on either side of the point where the clamp is applied. The construction and mounting of the bars therebeyond is of no moment so far as the present invention is concerned. However, in the disclosure employed here, for purposes of illustration, these bars are evenly spaced throughout their length, and at the ends of the bump-

er are rebent, as shown at 12 in Fig. 1. The extremities of these bars are attached to a rear bumper bar 13 by means of plates 14, which are generally triangular in shape, the bars 10 and 11 being each attached to a plate 14 by a rivet 15, and the bar 13 being attached to each of the plates 14 by two rivets 16. The bars 10 and 11 are provided in their outer surfaces with longitudinal grooves 17 extending throughout the length of the bars.

At the middle of the bumper I provide means for clamping the bars 10 and 11 to the rear bar 13, and also for clamping the bars 10 and 11 in fixed position with respect to each other, that is, means for definitely spacing them apart and preventing them from spreading. This clamp comprises an outer plate 18, an inner plate 19 and a bolt consisting of a threaded stem 20, which is mounted in the plate 18 and extends through a suitable hole in the plate 19. This stem or bolt 20 also extends through a hole in the rear bar 13 of the bumper, and the parts may be drawn up into clamping relation and held there by means of a nut 21 with a lock washer 22 interposed between it and the bar 13. The plate 18 carries on its rear side two bosses 23, which are of a size to fit snugly within the lower groove 17 of the upper bar 10 and the upper groove of the lower bar 11.

Now when the nut 21 is drawn up tightly, clamping the bars 10 and 11 between the plates 18 and 19, the bosses 23 cooperate with the grooves 17 in which they rest to effectively prevent any relative movement of the bars 10 and 11 in their common plane, either toward or away from each other. The plate 18, it will be observed, is comparatively small, not extending more than half way across the width of the bars 10 and 11, and it will be observed further that no spacer block between these bars is required. The plate 18 may conveniently carry an emblem 24 if desired.

It may be desirable, in some cases, to employ my clamp at points other than the middle of the bumper, or where the rear bar lies adjacent to the impact bars, and in such cases the clamp is identical with that herein illustrated, except that inasmuch as the bolt does not then extend through the bar 13 its length may be correspondingly reduced.

Figures 5 and 6 show the invention applied to use with impact bars 25 and 26 having but a single groove 27. The outer clamp plate

28 has bosses 29 on its rear surface similar to the bosses 23 previously described. But in this modification I have also illustrated a pair of lugs 30 integral with and extending 5 inwardly from the plate 28, which I may employ instead of the usual single spacing block with the use obviously of very much less metal. These lugs 30 are of some assistance in assembling the bumper and also assist in 10 spacing the bars 25 and 26 apart, being particularly useful for the latter purpose should the nut 21 become loosened, but these lugs are not at all essential, as the bosses 29 co- 15 operating with the grooves 27 will maintain the bars 25 and 26 in proper position under all normal conditions.

Having thus described my invention what I claim is:

1. In a bumper for automobiles, a pair of 20 substantially parallel impact bars spaced apart, each of said bars having a longitudinally extending groove in its outer face, and a clamp for said bars comprising a plate overlying the grooved surfaces of said bars, said 25 plate being provided with bosses of a width to fit said grooves, a second plate overlying the opposite surfaces of said bars, and a bolt joining said plates between said bars.
2. In a bumper for automobiles, a pair of 30 impact bars having substantially parallel portions spaced apart in the plane of the

bars, each of said bars having a longitudinally extending groove in its outer face, a clamp for said bars comprising a plate overlying the grooved surfaces of the bars, said plate being provided with bosses of a width to fit 35 said grooves, a second plate overlying the opposite surfaces of said bars, a third bar upon the opposite side of said second plate opposite the said space between the first 40 named bars, and a clamping bolt located in said space and securing together said plates and third bar.

3. In a bumper for automobiles, a pair of impact bars having substantially parallel 45 portions spaced apart in the plane of the bars, each of said bars having a longitudinally extending groove in its outer face, a clamp for said bars comprising a plate overlying the outer surfaces of both bars, said plate being provided with bosses of a width to fit 50 said grooves, a plate overlying the inner surfaces of both bars, and a bolt extending through the space between the bars for holding said plates together, and means for spacing said 55 bars apart comprising a pair of lugs extending from one of said plates into the space between the plates and between the bars.

In testimony whereof, I hereunto affix my signature.

GEORGE W. VEALE.
